JOHN H. D. PETERSEN AND ALBERT J. SAYERS, OF CHICAGO, ILLINOIS, ASSIGNEES TO
LINK-BELT COMPANY, A CORPORATION OF ILLINOIS.

ROTARY MINE-CAR DUMP.

1,287,093.

Specification of Letters Patent. Patented Dec. 10, 1918.

Application filed January 7, 1918. Serial No. 210,767.

To all whom it may concern:

Be it known that we, JOHN H. D. PETERSEN and ALBERT J. SAYERS, citizens of the United States, residing at Chicago, in the county of Cook and State of Illinois, have invented a certain new and useful Improvement in Rotary Mine-Car Dumps, of which the following is a specification.

Our invention relates to rotary mine car dumps wherein the cars are successively placed upon a rotary cradle and turned over by the rotation of the cradle to dump their contents. One of the objects of our invention is to provide means whereby each car when it has reached its proper position upon the cradle may be arrested no matter how rapidly it is traveling without undue load or being placed upon any part of the cradle or dumping mechanism. Another object of our invention is to provide means whereby the car may be more or less suddenly arrested in its movement and whereby the shock of arresting the car may be carried partially by the cradle and partially by an abutment therefrom.

In our invention we provide a spring buffer or abutment adapted to be engaged by any suitable part of the car preferably the wheels. This abutment when struck by the car in movement compresses a spring between it and the cradle. This spring is not strong enough to carry the full load and a plunger moving with the abutment engages a plunger removed from the cradle and compresses a powerful spring. The auxiliary spring on the cradle makes sure that the plunger mounted on the cradle will be held in the retracted position until the car is about to be stopped; thus there is no danger of interference by the plunger for a normal operation of the cradle.

Our invention is illustrated more or less diagrammatically in the accompanying drawings, wherein

Figure 1 is a side elevation;

Fig. 2 is a section along the line 2—2 of

Fig. 1.

Like parts are indicated by like characters in all the figures.

The dumping cradle is made up of a cross bridge A. This bridge is more or less rectangular frame work made up of channel beam sections as indicated. It carries track rails A¹, A¹ extending throughout the length thereof and is supported by means of

a plurality of circular roller tracks A², A² as indicated. In our preferred form we have shown two such tracks one at either end. There might be more or they might be differently arranged. These roller tracks are supported on grooved driving and supporting rollers A³, A³ mounted on shafts A⁴ in bearings A⁵ on supporting abutments or piers A⁶ and adapted to be rotated by power applied from any suitable source not here shown. The roller track members are braced by the beams A⁷ as indicated so that the cradle is properly stiffened and the load will be properly supported no matter what the position thereof. A⁸ is an ordinary mine car mounted on wheels A⁹ adapted to run along the tracks A¹. This car is provided with flanges A¹⁰ on the sides thereof and adapted to run under flanges A¹¹ on the beams A⁷ whereby when the car is in position on the cradle it is held on the track no matter what the angular position thereof.

B, B are track rails whereby cars may be led from any point not here shown onto the track rails A¹ on the cradle because these rails B, B are arranged on the supporting members B¹ in line with the track rails A¹ when the cradle is in the normal loading position. B², B² are discharge track rails in register with the track rails A¹ A¹ leading away from them so that the empty car may be conducted away after it has been dumped in the cradle.

D is a U-shaped support or bracket downwardly depending from the bridge A. It carries a control shaft D¹ adapted to be rotated at the will of the operator in any suitable manner not here illustrated. D² is an operating lever rigidly mounted on the shaft D¹ having two overhanging ends to each of which are pivotally secured the reach rods D³. These reach rods D³ are pivoted to the downward ends of the stop levers D⁴. These stop levers D⁴ are feathered upon the shafts D⁵ one on either side of the track rails A¹. Buffer members D⁷ are rigidly mounted on the shaft D⁵ and are adapted when in the position shown in full lines to rest one upon each of the rails to engage the mine car wheels and stop the car. These buffers may be withdrawn from their stopping position by a rotation of the controlling shaft thus permitting the mine cars to pass. The rotation of this shaft may be controlled by the operator through a lever, not

shown in the drawings, directly attached to the shaft, or through a gearing, with or without the intervention of motive force. The part may or may not be directly 5 manually operated.

Referring now to one side of the stop mechanism, as both parts are the same, E, E, are brackets in which the shafts D⁵ are slidably mounted. Between them and abutting 10 against one of them is a spring E¹ surrounding the shaft D⁵ and engaged at its other end by a collar E² rigidly mounted on the shaft D⁵. The parts are so positioned that the shafts D⁵ together with the buffer carried thereby are normally held in the retracted position with the spring extended to fill the space between two of the brackets, the shaft being withdrawn to the inner limit of its excursion, the end of the shaft 15 projecting outwardly a short distance beyond the end of the cradle but retracted so far that it does not interfere with the rotation of the cradle by engaging any of the fixed parts surrounding it.

20 F is a stop plunger slidably mounted in brackets F¹. It has a curved surface bumper held in opposition to the end of the shaft D⁵. F³ is a spring between and in engagement with one of the brackets F¹ surrounding the shaft F and engaged at its other end by a collar F⁴ rigid on the shaft F. This shaft F is held by the spring F³ yielding toward the end of the shaft D⁵, but its motion is limited by the engagement 25 of the collar F⁴ with the bracket F¹ so that there is a distinct clearance between the end of the shaft D⁵ and the bumper head F² when the parts are in the normal working position.

40 It will be evident that while we have shown in our drawings an operative device, still many changes might be made both in size, shape and arrangement of parts without departing materially from the spirit of 45 our invention and we wish, therefore, that our drawings be regarded as in a sense diagrammatic.

The use and operation of our invention are as follows:—

50 A car to be dumped is run upon the dumping cradle. The operator places the bumpers by operating machinery in any suitable manner so that the abutments are in the path of the car wheels and the car 55 wheels come in contact with them. This forces the bumper members forward compressing the springs and making the cradle carry a part of the load. Long before the springs on the cradle have reached the end 60 of their excursion the shaft carrying the bumper engages a shaft on the fixed abutment and heavier springs on the fixed abutment come into operation and stop the car. As soon as the shock or power of the car has 65 been distributed both springs will expand

again and the lighter spring on the cradle will force the car back a short distance until each of the shafts on the cradle has disengaged from the bumper head on the shaft so that there will be no danger of any 70 parts interlocking to prevent rotation of the cradle.

It will be understood, therefore, that these two sets of springs operating successively 75 distribute the shock of stopping the car and reduce the blow upon the cradle itself to a point where no danger need be anticipated from that source. The spring on the cradle forces the parts back into the normal position and the car is held by this spring after 80 it has come to rest. The parts are free and there is no possible interference of the rotary movement of the cradle.

We claim:

1. The combination with a rotary mine 85 car dump of means on the dump for arresting the movement of the car, and means removed from the dump for absorbing energy thus generated, and a discontinuous connection between said means.

2. The combination with a rotary mine car dump of means for stopping the car on the dump and means partially on the dump and partially removed from the dump for absorbing the energy thus released and a discontinuous connection between said means.

3. The combination with a rotary mine car dump having a track thereon, the axis of rotation of the dump being parallel with the track, of means on the dump for arresting 90 the movement of the car, and means removed from the dump for absorbing energy thus generated.

4. The combination with a rotary mine car dump of means on the dump for stopping 95 the car and yielding means partially on the dump and partially removed therefrom for absorbing the energy thus released and a discontinuous connection between such yielding means.

5. The combination with a rotary mine car dump of a car stop on the dump comprising an abutment adapted to engage the car, a slideable shaft carrying said abutment, a spring on the dump adapted to yieldingly 100 resist the movement of such shaft, a plunger removed from the dump in line with the shaft and a spring adapted to yieldingly resist the movement of such plunger.

6. The combination with a rotary mine car dump of a car stop on the dump comprising an abutment adapted to engage the car, a slideable shaft carrying said abutment, a spring on the dump adapted to yieldingly 105 resist the movement of such shaft, a plunger removed from the dump, the spring on the dump being adapted normally to hold the end of the shaft out of engagement with the end of the plunger.

7. The combination with a rotary mine 110

car dump of means for stopping cars on the dump comprising a removable spring supported car engaging abutment, capable of connection to manual control means for moving said abutment into and out of the operating position and means removed from the dump for absorbing energy generated by the stoppage of the car.

8. The combination with a rotary mine car dump of means for stopping cars on the dump comprising a removable spring supported car engaging abutment, capable of connection to manual control means for moving said abutment into and out of the operating position and means removed from the dump for absorbing energy generated by the stoppage of the car, such means comprising a spring held plunger in register with and normally out of contact with such abutment.

9. The combination with a rotary mine car dump of means for stopping cars on the dump comprising a removable abutment adapted for connection to manual control means for thrusting it into or out of register with the car, a spring held shaft upon which the abutment is mounted, a spring held plunger removed from the dump in register with the spring held shaft, the spring on the shaft being adapted to normally hold the ends of the plunger and shaft out of engagement one with another.

10. A rotary car dump comprising a rotary cradle, car tracks thereon, means for rotating the cradle, a plurality of car stops mounted on the cradle and adapted to rest on the tracks to engage the car wheels, spring held shafts upon which such stops are mounted, spring held plungers supported independent of the cradle in register with such spring held shafts and adapted to be moved against such springs by movement of the shafts.

11. The combination with a rotary mine car dump adapted to rotate on an axis parallel with the path of travel of the car, of yielding means on the dump for stopping the car, yielding means adjacent the dump for absorbing the energy transmitted by the first means, said yielding means mounted on the dump being adapted to withdraw from contact with the adjacently mounted energy absorbing means, to permit the unimpeded rotation of the dump.

12. The combination with a rotary mine car dump adapted to rotate on an axis parallel with the path of travel of the car, of yielding means on the dump for stopping the car, yielding means adjacent the dump for absorbing the energy transmitted by the first means, said yielding means in line with said means mounted on the dump, the stop-

ping means on the dump being adapted to withdraw from contact with the adjacently mounted energy absorbing means to permit 65 the unimpeded rotation of the dump.

13. The combination with a rotary mine car dump adapted to rotate on an axis parallel with the path of travel of the car, of yielding means on the dump for stopping 70 the car, yielding means adjacent the dump for absorbing the energy transmitted by the first means, said yielding means mounted on the dump being adapted to withdraw from contact with the adjacently mounted energy 75 absorbing means to permit the unimpeded rotation of the dump, the car stopping means and the energy absorbing means being disposed parallel with the dump track 80 and in line with each other.

14. The combination with a rotary mine car dump of means on the dump for arresting the movement of the car, and means removed from the dump for absorbing the energy thus generated, and a discontinuous 85 connection between said means disposed to permit the rotation of the dump.

15. The combination with a rotary mine car dump of means on the dump for arresting the movement of the car and means removed from the dump for absorbing the energy thus generated, and a discontinuous 90 connection between said means, said connection automatically broken, when the movement of the car is arrested.

16. The combination with a rotary mine car dump of means on the dump for arresting the movement of the car and means removed from the dump for absorbing the energy thus generated, and a discontinuous 100 connection between said means, said connection automatically broken, when the movement of the car is arrested, and normally permitting rotation of the dump.

17. The combination with a rotary mine car dump adapted to rotate on an axis parallel with the path of travel of the car, of yielding means on the dump for stopping the car, yielding means adjacent the dump for absorbing the energy transmitted by the first means, said yielding means mounted on the dump being adapted automatically to withdraw from contact with the adjacently mounted energy absorbing means, when the car is stopped, to permit the unimpeded rotation of the dump.

Signed at Chicago, in the county of Cook and State of Illinois, this 19th day of December 1917.
